(57) **CLAIM**

The ornamental design for an automobile exterior, as shown and described.

DESCRIPTION

FIG. 1 is a front perspective view of an automobile exterior showing our new design;

FIG. 2 is a rear perspective view thereof;

FIG. 3 is a front view thereof;

FIG. 4 is a rear view thereof; and,

FIG. 5 is a side view thereof.

It will be understood that the broken lines shown in the drawings illustrate portions of the automobile exterior that form no part of claimed design.
